(57) CLAIM

The ornamental design for set of handles for an article of cookware, as shown and described.

DESCRIPTION

FIG. 1 is a front perspective view of set of handles for an article of cookware showing my new design;

FIG. 2 is an enlarged perspective view of one of the handles shown separately for clarity of illustration;

FIG. 3 is a top plan view of FIG. 1;

FIG. 4 is a bottom plan view of FIG. 1;

FIG. 5 is a side view of FIG. 1;

FIG. 6 is another side view of FIG. 1;

FIG. 7 is a front view of FIG. 1; and,

FIG. 8 is a rear view of FIG. 1.

The broken lines are for illustrative purposes only and form no part of the claimed design.
